Attorney George H. Canby

UNITED STATES PATENT OFFICE.

OSCAR GASSETT, OF BOSTON, MASSACHUSETTS, ASSIGNOR TO THE UNION SWITCH AND SIGNAL COMPANY, OF PITTSBURG, PENNSYLVANIA.

RAILWAY ELECTRIC SIGNAL APPARATUS.

SPECIFICATION forming part of Letters Patent No. 267,979, dated November 21, 1882.

Application filed January 3, 1882. (No model.)

To all whom it may concern:

Be it known that I, OSCAR GASSETT, of Boston, county of Suffolk, State of Massachusetts, temporarily residing at Sewickley, county of Allegheny, State of Pennsylvania, have invented or discovered a new and useful Improvement in Railway Electric Signal Apparatus; and I do hereby declare the following to be a full, clear, concise, and exact description thereof, reference being had to the accompanying drawings, making a part of this specification, in which—like letters indicating like parts—

Figure 1 shows the electrical apparatus which I employ, arranged in connection with a diagram of a railway-track; and Figs. 2, 3, and 4 are detached views, showing different positions of the electrical devices at different times during their operation.

My present invention relates more particularly to an apparatus for electrically actuating the signals in a block signaling system of a single-track road, so that the signals will be properly actuated in whichever way the trains may be running. It involves a normally-closed track-circuit at each end of the block, and each such track-circuit excites an electro-magnet, so as to close a circuit at the opposite end of the block, which latter circuit includes the signaling-magnet which actuates the signal at that end of the block. The track-rails are insulated at the ends of the block, and also at or near the middle, and between insulated points they are electrically connected, rail end to rail end. Then the short-circuiting of either end section of track sends the signal at the other end of the block to "danger." The track-block is formed by insulating material inserted at its ends, as at $r' r''$, and the block so formed is divided into two sections, R R', by like means, as at r^2 , at any desired point between the ends—say at or near the middle. The left-hand end track-circuit, No. 1, is formed by battery a^2 , wire 11, track-rails x , wire 7, to post s^4 , wire 18, to and through the coil of electro-magnet A' ; thence by wire 19 to post s^3 ; thence by wire 8 and rails x' and wire 12 back to battery a^2 . This circuit being normally closed excites the electro-magnet A' , so as to cause it to attract its armature A^2 , and the tail-piece

A^3 thereof is brought against an electrical contact, D, so as thereby to close and keep closed a circuit, No. 4, which, commencing from a battery, a' , at the right-hand end of the block, passes by wire 4 to and through the signaling-magnet B' ; thence by wire 15 to post s^8 ; thence by wire 16, contact D, tail-piece A^3 , wire 17 to post s^7 , by wire 25 to post s^6 , by wire 5 to track-rails x^2 , and by wire 3 back to battery a' . The signal at that end of the block, of any desired construction, is connected by suitable interposed devices with the signaling-magnet B' , so that when excited it will hold the signal at "safety;" but as such signals and intermediate connections suitable for such use are well known in the art I have not thought it necessary to show them. Track-circuit No. 2, at the right-hand end of the block, commences from battery a , follows wire 1, track-rails x^2 , wire 5, to binding-post s^6 ; thence by wire 20 to and through the coils of electro-magnet A, wire 21, to binding-post s^5 ; thence by wire 6, track-rails x^3 , and wire 2 back to battery a . This circuit normally closed excites electro-magnet A, so as to cause it to attract its armature A^4 , and thereby the tail-piece A^5 of the latter is brought against the adjustable contact D'. This forms a closed signaling-circuit for the other or left-hand end of the block, such circuit (No. 3) starting from the battery a^3 and following wire 14 to binding-post s^4 ; thence by wire 23, contact D', tail-piece A^5 , wire 22, post s^2 , wire 24, post s^3 , wire 8, track-rails x' , wire 10, to and through signaling-magnet B, and thence by wire 9 back to the battery a^3 . By this means the magnet B is excited, and being supplied with a suitable signal and operating mechanism, as before described with reference to B', it holds its signal normally at "safety."

Assuming, now, that a train approaches from the left, as indicated by arrow w , its first effect on entering section R will be to short-circuit No. 1 circuit, so as to cut out electro-magnet A' from the influence of battery a^2 , release the armature A^2 , so that through the action of retractile spring c the tail-piece A^3 will break contact with D and go to insulated stop d , as indicated in Fig. 2. This will break circuit No. 4, demagnetize signal-magnet B' , which is included in that circuit, and let its signal go

to "danger" under the influence of a weight, spring, or other like means. Hence the moving train will be thereby protected as against trains coming from the opposite direction. As soon as the forward end of the moving train passes the insulating-point ¹² it short-circuits No. 2 circuit, so as to cut out electro-magnet A from the influence of its battery a, with the result of releasing its armature A⁴, so that its tail-piece A⁵, under the influence of its spring c', will move away from its contact D', thus breaking circuit No. 3 and demagnetizing the signaling-magnet B, which is included in said circuit, and letting its signal go to "danger," in like manner as at B'. This signal will then protect the rear of the moving train as against trains following; but the tail-piece A⁵, instead of going to stop d', comes against the end of the tail-piece A³, previously dropped, as indicated in Fig. 3. Each of these tail-pieces is provided with a hook, e'e', so made and proportioned that the tail-piece which drops last will come, with its hook, outside the free end of the other. Thus in the case supposed the hook e' of the tail-piece A⁵ will come outside, so as to be in position to engage the free end of the tail-piece A³. With the devices in the position thus indicated the tail of the train will pass off of section R, with the result of restoring circuit No. 1, so as to re-excite magnet A' and cause it to attract its armature A². In order, now, to prevent this action from restoring circuit No. 4 by making contact at D, and thereby setting the signal of magnet B' at "safety," I use the hook e' of tail-piece A⁵ to lock the tail-piece A³, as indicated in Fig. 4. Hence the signals at both ends of the block will remain at "danger" until the moving train shall have passed entirely off the block. As soon as this happens circuit No. 2, through battery a, is restored, so as to again energize electro-magnet A, which then attracts its armature A⁴, swings back the tail-piece A⁵ to contact D', Fig. 1, and in doing so causes its hook e' to clear the end of tail-piece A³, so that the latter may, under the action of its already energized magnet, go to its contact D. In this way circuits Nos. 3 and 4 are both restored, and the apparatus is again in normal condition and ready for the reception of a train from either direction.

In case a train approaches from the right, the same actions take place, but in reverse order. The train first runs onto section R', short-circuits No. 2 circuit, with the result of breaking circuit No. 3 at contact D', and letting the tail-piece A⁵ go to stop d', and putting the signal at B to a "danger" position, so as to protect the moving train as against trains coming from the left. When the forward end of the moving train enters section

R it short-circuits No. 1 circuit, with the result of breaking circuit No. 4 at contact D and putting the signal at B' to a "danger" position, so as to protect the moving train as against trains following; but in this case the tail-piece A³, instead of going to its stop d, as before, comes against the end of tail-piece A⁵, and with its hook e outside the end of A⁵, as illustrated by dotted lines in Fig. 4. Then when the train leaves section R' entirely and the magnet A is again energized by the restoration of circuit No. 2 the tail-piece A⁵ is locked by the hook e of tail-piece A³, so that it cannot go to contact D', and hence circuit No. 3 remains broken and both signals are continued at "danger;" but as soon as the train leaves the block entirely circuit No. 1 is restored, with the result of again energizing magnet A', and thereby bringing tail-piece A³ to contact D and unlocking tail-piece A⁵, so that it may go to contact D'. All circuits are thereby restored or closed, and the signals again go to their normal position of "safety." The presence of a car on either section, or the breaking of a rail, will short-circuit the corresponding section and send one or the other signals to "danger," so that if an engineer in approaching a block finds the signal at "danger" he will know that the track ahead of him is occupied, or else that it is unsafe.

The post s² and wire 24 may be omitted, and the wire 22 go to post s³; also, the post s⁷ and wire 25 may be omitted, and wire 17 go to post s⁶.

In a separate application filed herewith I have provided for doing substantially the same work as herein described by means of a fifth circuit through a relay so organized that such fifth circuit does the work of restoring the apparatus to normal condition, and such use of a relay is not included herein.

I claim herein as my invention—

An electrical block signaling apparatus adapted to be operated by a train running in either direction, having in combination a normally-closed track-circuit at or near each end of the block, each such track-circuit including an electro-magnet arranged to open and close a circuit extending to the opposite end of the block, a signal-magnet in each such latter circuit, and a locking mechanism adapted to prevent the reclosing of one broken signal-circuit until the proper time for the reclosing of both, substantially as set forth.

In testimony whereof I have hereunto set my hand,

OSCAR GASSETT.
